US0D1098922S

(12) **United States Design Patent** (10) **Patent No.:** **US D1,098,922 S**
(45) **Date of Patent:** **** Oct. 21, 2025**

(54) **BOTTLE**

- (71) Applicant: **PepsiCo, Inc.**, Purchase, NY (US)
- (72) Inventors: **William R. Eaton**, Southbury, CT (US); **Christopher Andrew Gregory**, New York, NY (US); **Niklas Gustafsson**, New York, NY (US); **Stephen Lim**, Chappaqua, NY (US); **Kai Xiang Lin**, Flushing, NY (US); **Christopher Nobles**, Brooklyn, NY (US); **Qiuchen Peter Zhang**, Mahwah, NJ (US)
- (73) Assignee: **PepsiCo, Inc.**, Purchase, NY (US)
- (**) Term: **15 Years**
- (21) Appl. No.: **29/899,905**
- (22) Filed: **Aug. 15, 2023**

Related U.S. Application Data

- (63) Continuation of application No. 29/865,156, filed on Jul. 11, 2022, now Pat. No. Des. 1,011,899, which is (Continued)
- (51) **LOC (15) Cl.** **09-01**
- (52) **U.S. Cl.** **USPC** **D9/552; D9/537**
- (58) **Field of Classification Search** **USPC** **D9/516, 529-530, 537-543, 549, 552, D9/565, 574-575**

CLAIM

The ornamental design for a bottle as shown and described.

DESCRIPTION

FIG. 1 is a top perspective view of a bottle showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of another embodiment thereof;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The dashed broken lines in the figures show portions of the bottle that form no part of the claimed design.

(Continued)

The dot-dash broken lines in the figures show boundaries that form no part of the claimed design.

1 Claim, 14 Drawing Sheets

Related U.S. Application Data

a continuation of application No. 29/707,640, filed on Sep. 30, 2019, now Pat. No. Des. 958,662.

(58) Field of Classification Search

CPC B65D 1/02; B65D 1/0223; B65D 2501/0036; B65D 1/0284

See application file for complete search history.
